(57) **CLAIM**

The ornamental design for a mobile toy robot, as shown and described.

DESCRIPTION

FIG. 1 is a perspective view of a mobile toy robot showing the design.

FIG. 2 is a left side view of a mobile toy robot.

FIG. 3 is a right side view of a mobile toy robot.

FIG. 4 is a rear view of a mobile toy robot.

FIG. 5 is a front view of a mobile toy robot.

FIG. 6 is a plan view of a mobile toy robot; and,

FIG. 7 is a bottom view of a mobile toy robot.

The broken lines represent portions of the design that form no part of the claim.
